US00D950048S

(12) **United States Design Patent** (10) Patent No.: **US D950,048 S**
Porkert (45) Date of Patent: **** Apr. 26, 2022**

(54) **SYRINGE INJECTION GUN**

- (71) Applicant: **Angela Bodmann**, Bobingen (DE)
(72) Inventor: **Stefan Porkert**, Augsburg (DE)
(**) Term: **15 Years**
(21) Appl. No.: **35/511,151**
(22) Filed: **Jul. 9, 2020**

(80) **Hague Agreement Data**

- Int. Filing Date: **Jul. 9, 2020**
Int. Reg. No.: **DM/211984**
Int. Reg. Date: **Jul. 9, 2020**
Int. Reg. Pub. Date: **Jan. 15, 2021**
(51) LOC (13) Cl. **24-02**
(52) U.S. Cl. **USPC D24/114**
(58) **Field of Classification Search**
USPC D24/112-115, 129-131, 133, 137, 140,
